United States Patent Office

Des. 195,184
Patented May 7, 1963

195,184

GARMENT DISPLAY STAND

Daniel E. Gelles, New York, N.Y.
(115 Ocean Ave., Brooklyn, N.Y.)

Filed May 16, 1962, Ser. No. 70,171

Term of patent 14 years

(Cl. D80—8)

Fig. 1

Fig. 2

I claim:

The ornamental design for a garment display stand, substantially as shown.
